FIG. 1

FIG. 2

FIG. 3

FIG. 1 is a side view of an electrical female connector primarily intended for connection to a dual-in-line integrated circuit and having two rows of terminals formed as pins for engaging in corresponding holes in a circuit board,

FIG. 2 is an end view of the connector of FIG. 1, and

FIG. 3 is a plan view of the connector of FIG. 1.

This application is a division of my earlier application Ser. No. D. 17,307, filed May 23, 1969, now Patent No. D. 223,000.

I claim:

The ornamental design of an electrical connector primarily intended for connection to a dual-in-line integrated circuit, as shown and described.
